UNITED STATES PATENT OFFICE.

HERMAN F. STUHR, OF CLEVELAND, OHIO, ASSIGNOR TO THE E. KONIGSLOW STAMPING & TOOL COMPANY, OF CLEVELAND, OHIO, A CORPORATION OF OHIO.

THREAD-OILING APPLIANCE.

Application filed February 24, 1925. Serial No. 11,117.

This invention relates to an oiling appliance for yarn and other fibrous threads, and the appliance is an improvement in the device shown and described in my application for patent of the United States, filed January 26, 1925, Serial No. 4,779. In the present instance my general object is to provide an oiling wheel adapted to rotate in a horizontal plane within or above a receptacle containing oil, the wheel being supported to rotate upon a stationary spindle from which it may be readily removed, and the oil being conveyed to the periphery of the wheel by means depending from the center of the wheel. A further object is to provide a mounting for such oiling wheels which will permit them to be shifted within the receptacle, especially in a trough-shaped body adapted to be situated adjacent a row of spindles or reels from which the yarn or thread is being unwound. Other objects are also embodied in other details of construction as will hereinafter more fully appear.

In the accompanying drawings, Fig. 1 is a top view of my improved oiling appliances comprising a single oiling wheel. Fig. 2 is a vertical section centrally of Fig. 1, the supply vessel being shown in elevation. Fig. 3 is a side view of my oiling appliance showing a slightly different form of receptacle. Fig. 4 is a sectional view transversely of the oiling appliance mounted upon a support which is adjustable lengthwise of a trough-shaped receptacle. Fig. 5 is a side view of the oiling wheel removed from the receptacle. Fig. 6 is a top view of the elongated receptacle showing two of my improved oiling appliances therein, and also disclosing a supply vessel seated within one end of the receptacle. Fig. 7 is a cross section corresponding to Fig. 4, showing an oiling wheel with a funnel depending portion which may be used to convey the oil upwardly to the absorbent body of the wheel.

Now referring to Figs. 1 and 2, the elongated receptacle R shown therein is of relatively shallow depth and contains a cross piece 2 adapted to provide a seat for a vessel 3 having a removable spout 4 through which a supply of oil may be fed to the receptacle and a fixed oil level established when vessel 3 is inverted and placed at rest upon the seat. Receptacle R may be of any desired length but as shown in Figs. 1 and 2

it is relatively short and is adapted to receive a single oiling wheel W. A stationary spindle or stem 5 extends upwardly from the bottom of receptacle R and is fixed thereto by a clamping sleeve 6 and a nut 7. Wheel W comprises a hollow shaft 8 adapted to receive spindle 5 and to fit loosely over the upper end of fixed sleeve 6. The upper end of spindle 5 is preferably rounded or pointed to support the wheel with pin bearing effect so that it may revolve very freely. The body 55 of wheel W comprises a number of flat disks 9 of felt or other absorbent material clamped between a flat top plate 10 and a dished bottom plate 11. The border portion of plate 11 is curved downwardly and extends as a 60 flange beyond the periphery of the absorbent body part 9 to permit surplus oil which may gather at the periphery of the wheel to drain back into the receptacle. In use wheel W 65 rotates rapidly, and surplus oil may be thrown outwardly from the periphery thereof, especially from flange 13, and therefore, a circular shield or drum 12 may be affixed 70 adjustably by bolts or screws 14 to the vertical wall of receptacle R, the shield or drum 75 extending upwardly any desired distance to encompass flange 13. The upper edge 15 of drum 12 may be rounded to avoid wear and tear on the thread or yarn T, which is caused 80 to pass around the felt body 9 of wheel W 85 under more or less tension. Brackets 16 affixed to the opposite sides of receptacle R 90 support open eye members 17 through which the yarn or thread T is caused to pass when brought in running engagement with the felt body of the wheel, and a small amount of oil is transferred to the oil or thread during 95 such running engagement. To avoid transfer of an excess amount of oil, I prefer to place some restraint upon the transfer of the oil from the receptacle to the felt body of the wheel. This may be accomplished in several ways and in Fig. 2 I show a tubular wick 18 100 sleeved over hollow shaft 8 and clamped at its upper end in facial contact with the felt body 9 of the wheel. The lower end of wick 18 extends into the body of oil contained within receptacle R, thereby drawing up a steady supply of oil by capillary action to the central part of the absorbent body of the wheel. The wheel is rotated by the running 105 thread and the oil is carried to the periphery of the wheel by centrifugal force. The

thread may be readily disengaged and lifted apart from the wheel and also as readily removed from the eye members whenever occasion requires, and the wheel itself may be lifted bodily from the spindle and replaced thereon whenever required.

In Fig. 3 the shield or drum 12 finds its equivalent in the elevated wall 19 of the modified form of receptacle R', although in this case the wall is not adjustable vertically. Where a deeper receptacle R' is used, I prefer to form side openings 20 within the wall opposite supply vessel 3 to permit the vessel to be easily removed so that the contents of this vessel may always be visible, and a glass or transparent vessel is preferred for this purpose.

Now referring to Figs. 4 to 6 inclusive, I have shown the identical wheel disclosed in Fig. 2 except that the central depending part of the wheel is shorter. An elongated trough-shaped receptacle R'' is also shown in which two or more oiling wheels may be supported. This receptacle may be of any length and a large number of oiling wheels may be mounted therein so that any number of spindles or wheels may be served in a knitting, weaving or other machine where it is common to employ rows of spindles or wheels from which the yarn or thread is unwound automatically in the operation of the machine. The distance between the spindles or wheels may vary on different types of such machines, and in that case it is an easy matter to adjust the oiling wheels to correspond by shifting the oiling wheels bodily within the trough-shaped receptacles. To that end I mount the supporting stem 5 for each wheel W upon a shiftable support 21, which in the present instance is shown as a flat bar bent to conform to the inner walls of the trough and formed with hook-shaped extremities 22 adapted to overhang the edges of the trough to permit set screw 23 to be used in clamping support 21 in any desired position of adjustment lengthwise of the trough. Hooks or open eyes 17' may be mounted upon the lateral extremities 22, and a shield or drum 12' may be adjustably affixed to and carried by support 21 around wall W, thus permitting the wheel and its associated parts to be shifted jointly to different positions upon the trough.

In Fig. 7 I show an organization of parts which is exactly the same as in Fig. 4, except that wheel W comprises a bottom plate 11 having a funnel shaped central wall 24 extending downwardly into the body of oil and reduced in diameter at its lower end to permit it to engage supporting stem 5. Perforations 25 may be formed within the lower end of the inverted cone or funnel 24 to permit oil to pass into the funnel chamber. Rapid rotation of the wheel will cause the oil to ascend the inclined wall of the funnel

and keep felt body 9 sufficiently saturated with oil to properly oil the thread passing around the periphery of the wheel.

What I claim, is:

1. An appliance for oiling a running thread, comprising a receptacle containing oil, and an oiling wheel mounted upon a vertical axis and rotating in a horizontal plane, said wheel having a depending hub extending into the oil in said receptacle to feed oil to said wheel.

2. An appliance for oiling a running thread, comprising a receptacle containing oil, and a horizontal wheel of absorbent material having an oil lifting and feeding element extending downwardly therefrom at its axis in touch with the oil within said receptacle.

3. An appliance for oiling a running thread, comprising a receptacle, a wheel adapted to rotate in a horizontal plane above said receptacle, said wheel having a tubular extension at its bottom projecting into said receptacle and adapted to convey oil to said wheel.

4. An appliance for oiling a running thread, comprising a receptacle containing oil, a vertical stem extending upwardly within said receptacle, and a wheel engaged by the thread and mounted to rotate upon said stem, said wheel having a central tube sleeved upon said stem in touch with said liquid and adapted to feed oil to the surface engaged by the thread.

5. An appliance for oiling a running thread, comprising a receptacle, an upright stem within said receptacle, a wheel removably seated upon said stem adapted to be engaged by said thread, and having a hub portion extending into said receptacle and adapted to convey oil from said receptacle to said wheel.

6. An appliance for oiling a running thread, comprising a receptacle containing oil, an oiling wheel, oil feeding means for said wheel, and a shield encircling a part of the circumference of said wheel.

7. An appliance for oiling a running thread, comprising a receptacle, a thread oiling wheel rotatable in a horizontal plane within said receptacle, and a vertically adjustable shield adjacent said wheel.

8. An appliance for oiling a running thread, comprising a receptacle, a horizontal wheel within said receptacle having a flange at its periphery adapted to drain surplus oil back into said receptacle, and means centrally of said wheel adapted to convey oil upwardly thereto from the receptacle.

9. An appliance for oiling a running thread, comprising an elongated receptacle, a thread oiling wheel mounted upon a support which is horizontally and vertically adjustable in respect to said receptacle, and means upon said support adapted to guide a

thread in running contact with said wheels.

10. An appliance for oiling a running thread, comprising a receptacle containing oil, a supporting member movably mounted upon said receptacle, a vertical stem affixed to said supporting member, and an oiling wheel self-feeding out of said receptacle and rotatably mounted upon said stem.

11. An appliance for oiling a running thread, comprising a trough-shaped receptacle, a yoke-shaped supporting member bridging said receptacle having thread guiding devices thereon, a vertical stem affixed to said supporting member, a wheel

supported to rotate upon said stem having a 15 circumferential oiling surface, and means depending from said wheel and connected therewith adapted to feed oil upwardly thereto from said receptacle.

12. An appliance for oiling a running 20 thread, comprising an elongated receptacle, and a thread oiling wheel mounted to rotate in a horizontal plane and vertically adjustable to any desired operating position therein.

In testimony whereof I affix my signature.

HERMAN F. STUHR.
